UNITED STATES PATENT OFFICE.

ALBERT M. PIGEON, OF PHILADELPHIA, PENNSYLVANIA, ASSIGNOR TO PIGEON MACHINE COMPANY, OF PHILADELPHIA, PENNSYLVANIA, A CORPORATION OF PENNSYLVANIA.

CIRCULAR FASHIONING KNITTING-MACHINE.

1,213,003.

Specification of Letters Patent. Patented Jan. 16, 1917.

Application filed May 25, 1911. Serial No. 629,260.

To all whom it may concern:

Be it known that I, ALBERT M. PIGEON, of the city of Philadelphia, county of Philadelphia, and State of Pennsylvania, have 5 invented certain new and useful Improvements in Circular Fashioning Knitting-Machines, whereof the following is a specification, reference being had to the accompanying drawings.

10 The invention relates to new and useful improvements in circular fashioning knitting machines, and more especially to knitting machines of the cylinder type wherein the cylinder may be rotated for circular knitting or oscillated at certain intervals, if desired.

15 A further object of the invention is to provide a picker with a chamfered end which allows the picker to give the full movement 20 to the needle, *i. e.* from active to inactive position or vice versa, without additional cams for completing the movement thereby decreasing the extent of movement of the needle and increasing the efficiency of the 25 picker operating mechanism.

30 An object of the invention is to provide a narrowing picker which is so constructed as to engage the butts of the needles, or the operating parts for the needles, and to move 35 the needles from active position to idle position, the lifting of the needle and the disengagement of the same from the picker being brought about by the movement of the needle cylinder.

35 A further object of the invention is to provide a widening picker which operates to carry down two needles at the same time from idle position to active position, which picker is also so constructed as to operate 40 upon the advance needles at both ends of the idle series, during the oscillating movements of the cylinder.

45 A further object of the invention is to provide a construction of needle cylinder and needle jacks, whereby when the needle jacks are placed in the needle slots, the cylinder forms substantially one solid band, so that all liability of bending the ribs of the cylinder through the engagement of the 50 butts of the needles with the pickers, or with other operating parts, is avoided.

The main object is to strengthen the wall of the cylinder by filling the slots so that the accidental displacement of the butts will

allow the butts to be broken off without the 55 liability of fracturing the cylinder wall.

A further object of the invention is to provide means for throwing out one of the switch cams, and also one of the pickers, for the purpose of leveling the needles to place 60 the needles in position for transferring.

These and other objects will in part be obvious, and will in part be hereinafter more fully described.

In the drawings, which show by way of 65 illustration one embodiment of the invention, Figure I, is a plan view of the needle cylinder, the supporting shelf and the controlling parts for the needles. Fig. II, is a partial plan sectional view, showing the sup- 70 porting shelf, the needle cylinder, the pickers and the controlling cams for the needles, the parts being positioned for circular knitting. Fig. III, is a view similar to Fig. II, with the parts positioned for the oscillating 75 of the cylinder to form heel and toe pockets. Fig. IV, is a view more or less diagrammatic, showing the stitch cams, the pickers, and the cams for raising and lowering the needles. Fig. V, is a detail view, showing 80 one of the narrowing pickers, lifting a needle butt from active to idle position. Fig. VI, is a similar view, showing the butt of the needle at the point of slipping off from the picker. Fig. VII, is a plan view, show- 85 ing a portion of the needle cylinder and one of the narrowing pickers at the point of releasing the needle butt. Fig. VIII, is a detail view, showing the first engagement of the picker with the needle butt. Fig. IX, is 90 a detail view, showing the needle butt slipping from the end of the picker. Fig. X, is a detail view, showing the widening picker at the point of releasing two of the needle butts carried to active position thereby. Fig. 95 XI, is a plan view of the picker, and a sectional view of the needle cylinder with the parts as shown in Fig. X. Fig. XII, is a detail sectional view through the cylinder showing the needle and needle jack for controlling the same. Fig. XIII, is a sectional view on the line XIII, XIII of Fig. XII.

The invention herein shown in general forms a part of the machine shown and described in my copending application Serial 105 No. 633,938 filed June 19, 1911.

The machine consists of a needle cylinder 1, which is provided with a plurality of

spaced ribs 2, forming needle slots to receive the needles. The needles 4, as herein shown, are of the spring beard type. Each needle is detachably connected with a needle jack 5. These needle jacks engage the needle slots, and are substantially the same width as the ribs 2, of the cylinder, and substantially the same thickness as the distance between the ribs forming the needle slots, so that when the needle jacks are placed in the needle slots, the entire space between the ribs is filled by the jacks, and the cylinder presents at this point substantially one solid band. By this construction of needle jack, I am able to make a very small needle cylinder, having comparatively thin ribs.

The needle is bent outwardly at its lower end and extends down the outer face of the needle jack, and the extreme lower end of the needle is formed with a hook 6, which engages a slot in the needle jack at a point directly above the butt 7, of the jack 5. When the needle is connected with the jack, the same will assist in holding the jack in place in the needle slots. The needles are held in place at a point above the jack by flexible bands 8, which are of the usual type.

While I have shown and described the needle as attached to a needle jack having a butt, it is obvious from certain aspects of the invention, that the butts may be formed directly in the needles, and hereinafter I will refer to these butts 7, as the needle butts.

The needles are formed in two series, that is, one series of the needles has short butts, while in the other series each needle is provided with a long butt. During the rotation of the cylinder, the needles are raised and lowered to receive the yarn, to form the loops and to shed the previous loops carried by the needles by stitch cams which are carried by a cam ring 9. The stitch cam 10, operates upon all the needle butts during the rotation of the cylinder, and upon the short needle butts only upon the oscillation of the needle cylinder in one direction. The stitch cam 11, operates solely on the needle butts in action when the cylinder is oscillated in the opposite direction.

In order to carry the needle butts down into active engagement with the stitch cams, I have provided switch cams 12, and 13. The switch cam 12, is formed with a long tapered finger 14, which normally rests against the edge of the stitch cam 10. This finger 14, is carried by a shank 15, which is mounted to slide in a bearing 16, carried by the shelf 17, projecting from the frame of the knitting machine. The switch cam is pressed forward against the needle cylinder, or to active position by a spring 18. A coiled spring 19, engaging a stud on a collar 20, normally rotates the finger 14, so as to hold the same in engagement with the edge

of the stitch cam 10. When the needle cylinder is rotating in the direction of the arrow, Fig. IV, the needle butts will engage the finger 14, of the switch cam and will be guided down the incline of the stitch cam 10. When the cylinder is moved in the opposite direction, the butts will engage the other side of the switch cam finger 14, which will turn about the axis of its supporting shank against the tension of the coiled spring 19, and allow the needle butts to pass. The switch cam 13, is in all respects similar to the switch cam 12, except that the coiled spring normally moves the finger of the switch cam 13, in the opposite direction, and presses the same against the edge of the stitch cam 11, at the opposite side thereof from the stitch cam 10. In dotted lines in Fig. IV, I have shown the position of the switch cam 13, which allows the needle butts to pass thereby.

As a means for raising the long butt needles to idle position, or depress the same to active position, I have provided a raising cam 21, and a lowering cam 22. These cams 21, and 22, are mounted on a bracket, which is pivoted on a post 23. When one cam is swung into action, the other cam is swung out of action, as the cams are on opposite sides of the pivot point. When the parts are positioned as shown in Fig. III, it will be obvious that the long needle butts will engage the raising cam 21, and be moved from an active position to an idle position. When the cam 22, is moved in against the needle cylinder, then the long butt needles will be engaged thereby, and be caused to move from the idle position to the active position. The cams 21, and 22, are moved into and out of position by an arm 24, which carries spaced collars 25. This arm 24, is connected to a second arm 26, which engages the arm 24, between the collars 25, and a spring 27, normally holds the collar 25, pressed against the arm 26. The arm 26, is carried by the clutch-shifting bar, so that when the mechanism is shifted in the well known way to cause the cylinder to oscillate, the raising cam 21, is thrown into action to lift the long butt needles to idle position. On the other hand, when the clutch is shifted to cause the cylinder again to rotate, the lowering cam 22, is thrown into action to depress the idle needle so they will be engaged by the switch cam 12.

In forming stockings with heel and toe pockets, it is necessary to narrow and widen these pockets. This is brought about by throwing out of action certain of the active needles, and by throwing into action certain of the idle needles, through the means of the narrowing and widening pickers.

The narrowing pickers, as herein shown, are two in number, and are so located that the switch cams are between the pickers.

One picker acts to raise the advance needle in the active series to idle position when the cylinder is moving in one direction, and the other picker acts to raise the advance needle to idle position when the cylinder is moving in the opposite direction. The picker 27, consists of a shank portion 28, which is pivoted on a stud 29, carried by a bracket mounted on the supporting shelf. This stud 29, is inclined so that as the shank 28, swings about the same, the picker finger 27, carried by the shank will swing in an inclined direction from one horizontal plane to another. When the needle butt engages the picker, it will be moved from one level to another level. The picker finger 27, is clamped in the shank by a suitable set screw 31. By this construction of separate finger and supporting shank, when a picker finger is broken, bent or worn, it may be easily removed and replaced at very little cost. The outer end of the picker, as more clearly shown in Figs. V to IX inclusive, is chamfered as at 32. The active side of the picker, that is, the side facing the needle butt which is to be lifted, is cut away to form a shoulder 33. As the cylinder rotates, the needle butt 7, will be carried on to the shoulder 33, and against the side face 34, of the picker, as shown in Figs. V, and VIII. The continued movement of the cylinder will cause the shank of the picker to swing about its inclined axis, and the needle to be raised in the needle slot to the position shown in Figs. VI, and IX. When the needle reaches this position, the angular position of the finger 27, is such that the needle butt will slip past the end of the picker finger. It will be seen by reference to Fig. VI, that the chamfered end of the picker underlies the butts of the already inactive needles, so that these needles are not interfered with during the motion of the picker, and the picker may therefore be so shaped as to carry the needle to full inactive position before releasing the same. In other words, this chamfered end forms a clearance for the butts of the inactive needles.

It will be apparent, therefore, that the picker herein shown engages the needle butt while at its lower level, and carries the needle butt to the extreme upper level, where the picker finger is released from the needle butt, through the movement of the needle cylinder, and the construction of the outer active end of the picker finger. Through this action of the picker which carries the needle from one extreme position to another, I am able to do away with the numerous cams usually employed to assist in carrying the needles from one level to the other, and furthermore shorter needles may be used and the distance through which the needles are carried to render the same inactive is reduced to a minimum.

The picker finger 35, is carried by a shank 36, pivoted on a stud inclined to the vertical, and carried by a supporting bracket on the supporting shelf of the machine. This picker 35, is like in construction, the picker 27, except that the shoulder of the picker finger 35 is on the opposite side, so as to co-operate with the advance needle on the opposite side of the series, and while the cylinder is moving in the opposite direction.

The function of the pickers for narrowing the heel and toe pockets, is so well known that further description thereof is not thought necessary.

The widening picker consists of a picker finger 37. This picker finger is rigidly carried by a yoke 38, see Fig. XI, which in turn is pivoted at 39, to a plate 40, which is also pivoted at 41, to a supporting bracket 42. The axis of the support for the plate 40, is practically at right angles to the pivotal axis of the yoke 38. In practice, I mount the picker so that its path of movement in either direction is in an angle, somewhat less than 45 degrees, preferably about 40 degrees. This is advantageous in reducing the friction and also serves to decrease the strain on the needle butts. A stop screw 43, is carried by the yoke 38, and when the picker is in the position shown in Fig. IV, this stop screw engages the plate 40, to prevent further upward swinging of the arm carrying the picker finger 37. A similar stop 44, limits the upward swing of the plate 40. A spring 45, is attached to the bracket 42, and at its free end engages the shank supporting the picker finger 37. This spring tends to force the picker finger upward, and to hold the same in the position shown in Fig. IV.

It will be readily understood that the shank supporting the picker finger 37, may swing about the axis 39, and the picker thereby moved in an inclined direction relative to the movement of the cylinder. The shank supporting the picker 37, may also be swung about the axis 41, in an opposite inclined direction relative to the movement of the needle cylinder. If, therefore, the picker is held in the position shown in Fig. IV, and a needle butt engages the same, the movement of the cylinder in one direction will swing the yoke 38, about its axis, and the movement of the cylinder in the opposite direction when the needle butt strikes the opposite side of the picker finger, will swing the plate 40, about its axis. When the picker finger is released from the needle butts, and is in active position, the spring 45, will at once return the same to the position shown in Fig. IV.

The forward end of the picker finger 37, is formed with a projecting shoulder 46, on one side, and a projecting shoulder 47, on the other side. These projecting shoulders

overhang the side walls of the finger, which is chamfered on its lower face, as at 48. The overhanging shoulders 46, and 47, are of sufficient width to engage two adjacent needle butts, so that when the cylinder is moving in one direction, two needles will be engaged by the widening picker, and be moved from the idle level to the active level, and when the needle butts reach the active level, the position of the picker finger is such that the butts will slide past the end of the finger, the chamfered surface of the lower face thereof, clearing the butts of the active series, so that the picker is released and may be returned to normal position through the action of the spring 45.

The function and action of the widening picker is so well known that further description thereof is not thought necessary. 20 In order that the needle cylinder may be rotated for circular knitting, it is essential to provide some means for throwing the widening picker out of action. This is accomplished in the present embodiment of 25 my invention by an arm 49, which is mounted on the pivot 50, and is operated by a second arm 51. A bar 52, may be controlled by the action of the machine, for moving the arm 49. When the arm 49, is swung 30 toward the needle cylinder, it will engage the plate 40, and swing the same, so as to force the picker finger 37, out of contact with the needle cylinder and to inactive position as shown in Fig. II.

35 In order to throw the narrowing picker 27, out of action, the lowering cam 22, is formed with an arm 53, which has a cam face 54, adapted to engage the stud 31, which secures the picker finger to the supporting 40 shank. When this lowering cam 22, is thrown into action to bring the long butt needles into active position, the picker will be engaged by this cam surface and moved away from the cylinder to inactive position 45 as shown in Fig. II. During the movement of the cylinder in the direction of the arrow in Fig. III, the picker finger 35, is inactive, and, therefore, it is not necessary to move this picker finger away from the needle 50 cylinder.

After the finishing of the knitted article, it is sometimes desirable to bring the needles all to the same level for the purpose of transferring the knitted article. If the switch 55 cam 12, is moved away from the needle cylinder, so as to allow the short butt needles to pass the same, then said short butt needles instead of being carried down into action with the stitch cam 10, will float over the 60 stitch cam. It is also necessary to move the picker finger 35, out of action in leveling the needles, so that these butts will not strike the same. In the ordinary knitting, the butts of the needles following the stitch 65 cam are carried underneath the picker 35,

so that it is not necessary to move it out of active position, but when the needle butts are not moved down by the switch cam 12, then it is necessary to move the picker to inactive position. If the machine is stopped 70 when the short butt needles are at the front of the machine, and out of engagement with the stitch cams, and the switch cam 12, moved out so as to allow the short butt needles to pass over the top of the stitch 75 cam, it will readily be seen that a half rotation of the cylinder will not disturb the level of the short butt needles, but as the switch cam is still in active engagement with the long butt needles, these needles will be raised to the inactive level whereupon 80 the cylinder may be readily removed, as all the needles are now at an inactive level.

As a means for simultaneously moving the switch cam 12, and the picker 35, out of 85 active position, I have provided a lever 55, which is pivoted at 56, to the frame of the machine, and is held by a spring 57, against a stop shown at 58. This lever at its outer end carries a rounded portion 59, which engages the collar 20, on the shank of the switch cam 12, and upon the swinging of the lever 55, the part 59, will engage the collar and move the switch cam out far enough to allow the short butt needles to pass. A second arm 60, is carried by the lever 55, and this arm engages a pin 61, on the shank of the picker 35, and raises the picker to inactive position, so as to allow the short butt 90 needles to pass the same. The arm 60, and 100 the end of the lever 59, are so positioned, relative to the parts which are operated by the same, so that the picker may be moved a sufficient distance to render it inactive, and the switch cam moved a slight distance and 105 only sufficient to withdraw it from coöperation with the short butt needles.

The operation of the devices above described will be obvious. The needle cylinder may be operated for circular knitting, 110 in which case the butts of all the needles will engage the switch cam 12, which carries the same down into engagement with the stitch cam, whereby the needles are depressed at the knitting point to shed the previous loop, 115 thereon and to draw a new fabric loop. At the proper time the cylinder is caused to oscillate and when the parts are shifted to bring about the oscillation of the cylinder, the arm 24, is thrown so as to bring the 120 raising cam 21, into operation, which engages solely the long butt needles and raises the same to an idle level. At the same time the long butt needles are rendered idle, the picker 27, is released by the outward movement of the lowering cam so that said picker is thrown into action. Upon the first reverse movement of the needle cylinder picker 35, will engage the butt of the first 125 needle in the active series, and raise the same 130

- to the idle level. On the reverse movement of the needle cylinder, the picker 27, will engage the butt of the advanced needle on the opposite side of the needles in the active series and raise the same to the idle level. This action continues until the narrowing of the pocket being formed is finished, after which the widening picker 37, is thrown into action, which will engage the 10 needle butts of the two advanced needles in the idle series and move the same down to the active level, reverse and continue widening. Upon the shifting of the clutch to cause the cylinder to rotate for circular 15 knitting, the lowering cam is brought into action through a movement of the arm 24, which lowers all the needles into active relation with the stitch cams. At this time, the picker 27, is thrown out of action.
- 20 When it is desired to level the needles, the lever 55, is moved by the operator which lever will first throw the picker 35, to inactive position and then move the switch cam 12, laterally so as to bring it out of engagement with the short butt needles, but allow the same to operate upon the long butt needles. The switch cam is thrown out so as to engage the long butt needles only when the short butt needles are at the front of the 25 machine. If the cylinder is then turned, the short butt needles will not be acted upon by the pickers, nor by the stitch cams, but will remain at the same level while the long butt needles passing through the stitch cams will 30 all be raised to the level of the short butt needles, provided, of course, that the needle cylinder is stopped when the long butt needles are at the front of the machine. By this arrangement I am able to bring all the 35 needles to a level by simply shifting to a slight extent, one of the stitch cams.
- It is obvious that minor changes in the 40 details of construction may be made without departing from the spirit of the invention as set forth in the appended claims.
- Having thus described my invention, I claim:
1. In a knitting machine, the combination of a needle cylinder, a series of needles having butts or the like carried thereby, a narrowing picker coöperating with said needle butts, said picker having a shoulder adapted to engage a needle butt at the lower active level, means for supporting said picker whereby the movement of the needle cylinder operates through the needle engaging the shoulder on the picker to move said picker to raise said butt to the full idle level, the upper face of said picker when raised to full extent being substantially in line with the under face of the butts of the idle needles, whereby said picker may pass underneath said butts and clear the same.
  2. In a knitting machine, the combination of a needle cylinder; a series of needles hav-
  - ing butts or the like carried thereby; a narrowing picker, said narrowing picker having a shoulder adapted to be engaged by the butt of the needle; means for pivoting said picker whereby the same swings about an inclined axis and carries the needle butt from a lower level to an idle level, the outer upper end of the picker being chamfered to clear the butts of the idle series and allow the butt of the needle to be raised to full idle level without disturbing the other idle needles.
  3. In a knitting machine, the combination of a needle cylinder; a plurality of needles carried thereby; needle jacks for engaging and moving said needles, each needle jack having a butt formed with a square outer lower corner; a picker having a shoulder for engaging the square corner of said butt; means for pivoting said picker, so that the same swings about an inclined axis to carry the needle from a lower level to an idle level, the upper end of said picker being chamfered to clear the butts of the already inactive series of needles.
  4. In a knitting machine, the combination of a needle cylinder; a series of needles having long butts and a series of needles having short butts carried by said needle cylinder; a raising cam for lifting the needles having long butts to idle level; a lowering cam for moving the needles with the long butts to active position, said cams being rigidly attached to a pivoted bracket on opposite sides of the pivotal point thereof, whereby when one cam is thrown into action, the other cam is positively thrown out of action; a narrowing picker; and a cam plate carried by the bracket supporting the raising and lowering cams for engaging and moving the picker to inactive position upon the moving into action of the lowering cam.
  5. In a knitting machine, the combination of a needle cylinder, a plurality of needles having butts or the like carried by the cylinder, a widening picker, a pivoted yoke supporting said widening picker, a pivoted plate engaging said yoke, the axis of the plate and the axis of the yoke being substantially at right angles to each other; a stop for limiting the upward swinging movement of the plate; a stop for limiting the upward swinging movement of the yoke; a spring engaging the picker for normally holding the yoke and plate in engagement with the stops, said picker consisting of a finger having oppositely disposed overhanging ledges adapted to engage two needle butts, said picker having a notched working end to engage a needle butt at the inactive level and through the movement of the cylinder depress said needle to full active level, said picker having its lower face cut away to clear the needles when said needles are at full lower level.
  6. In a knitting machine, the combination

- of a needle cylinder; a plurality of butt needles carried thereby; a widening picker; a pivoted yoke supporting said widening picker; a pivoted plate carrying said yoke, the axis of the yoke and the axis of the plate being substantially at right angles to each other; a stop for limiting the upward swinging movement of the plate; a stop for limiting the upward swinging movement of the yoke; a spring engaging the picker for normally holding the yoke and the plate in engagement with the stops; and means for rendering said widening picker inactive, consisting of a pivoted arm adapted to engage said plate and swing the same about its axis against the tension of the spring.
7. In a knitting machine, the combination of a needle cylinder; a plurality of butt needles carried thereby; a widening picker; a pivoted yoke supporting said widening picker; a pivoted plate carrying said yoke, the axis of the yoke and the axis of the plate being substantially at right angles to each other; a stop for limiting the upward swinging movement of the plate; a stop for limiting the upward swinging movement of the yoke; a spring engaging the picker for normally holding the yoke and the plate in engagement with the stops, said picker consisting of a finger having oppositely disposed overhanging ledges adapted to engage the two needle butts, the lower corner of said picker finger being chamfered to allow the same to clear the butts of the active series while throwing the needles engaged to full active level.
8. In a knitting machine, the combination of a needle cylinder; a plurality of needles, needle jacks engaging said needles, said needle jacks having butts formed with square upper corners; a widening picker consisting of a finger having overhanging ledges adapted to engage the butts on the needle jacks, and having its lower face chamfered so as to release and clear the butts of the needles when in active position.
9. In a knitting machine, the combination of a needle cylinder adapted to rotate and to oscillate; a series of short butt needles and a series of long butt needles carried thereby; stitch cams coöperating with said butt needles; switch cams for moving the butts into engagement with the stitch cams; pickers coöperating with the needle butts upon the oscillation of the cylinder; means for rendering one of said pickers inactive during circular knitting; and means for throwing out of action the other picker and moving the switch cam laterally from engagement with the short butt needles only, whereby said needles are leveled for transferring.
10. In a knitting machine, the combination of a needle cylinder adapted to rotate and to oscillate; a series of short butt needles and a series of long butt needles carried thereby; stitch cams coöperating with said butt needles; switch cams for moving the butts into engagement with the stitch cams; pickers coöperating with the needle butts upon the oscillation of the cylinder; means for rendering one of said pickers inactive during circular knitting; a lever having an arm for engaging the other picker, and an arm for engaging the switch cam and moving the same from engagement with the short butt needles.
11. In a knitting machine, the combination of a needle cylinder adapted to rotate and to oscillate; a series of short butt needles and a series of long butt needles carried thereby, stitch cams coöperating with said butt needles; switch cams for moving the butts into engagement with the stitch cams; pickers coöperating with the needle butts upon the oscillation of the cylinder; means for rendering one of said pickers inactive during circular knitting; a lever having an arm for engaging the other picker, and an arm for engaging the switch cam and moving the same from engagement with the short butt needles.

In testimony whereof, I have hereunto signed my name at Philadelphia, Pennsylvania, this eighth day of May 1911.

ALBERT M. PIGEON.
